(57) **CLAIM**

The ornamental design for an electromagnetic field generator, as shown and described.

DESCRIPTION

FIG. 1 is a perspective view of an electromagnetic field generator;

FIG. 2 is a front end view thereof;

FIG. 3 is a rear end view thereof;

FIG. 4 is a right side view thereof;

FIG. 5 is a left side view thereof;

FIG. 6 is a top view thereof; and,

FIG. 7 is a bottom view thereof.

In the drawings, the broken lines, including broken line illustrations of branding logos, show unclaimed portions of the electromagnetic field generator that form no part of the claimed design. The broken lines between the left and right sides of the design represent unclaimed ornamentation that form no part of the claimed design.
